United States Patent Office.

E. R. HALL AND WILLIAM H. TOWN, OF SYRACUSE, NEW YORK.

Letters Patent No. 97,393, dated November 30, 1869.

IMPROVEMENT IN SAWING-MACHINES.

The Schedule referred to in these Letters Patent and making part of the same

To all whom it may concern:

Be it known that we, E. R. HALL and WILLIAM H. TOWN, of Syracuse, in the county of Onondaga, and State of New York, have invented a new and valuable Improvement in Sawing-Machines; and we do hereby declare that the following is a full, clear, and exact description of the construction and operation of the same, reference being had to the annexed drawings, making a part of this specification, and to the letters and figures of reference marked thereon.

Figure 1 of the drawings is a central vertical longitudinal section of our invention.

Figure 2 is a top view of the same.

Our invention relates to sawing-machines, and consists in a novel arrangement of devices intended to serve as an efficient apparatus in the occupation of sawing wood into lengths.

The letter A of the drawings designates the frame of the machine, consisting of the uprights A' a', bed-pieces B B, ties C C, and girders E E'.

G designates the saw, fastened between the jaws formed in the end of the sliding bar H, which slides in a groove in the hanging guide-frame M.

The other end of the sliding bar H is pivoted to the pitman z, which is adjustable, and pivoted in turn to the perpendicular arm v of the lever V.

The lever V consists of the horizontal bar or fulcrum q, horizontal arm v', and perpendicular arm v.

The fulcrum q is pivoted, at the ends, in the uprights a' a'.

The horizontal arm v' of the lever is operated through the pitman r, by the crank-shaft s', on one end of which is keyed the fly-wheel t, and, on the other end, the spur-wheel u, which gears with the annular wheel K, operated by the pinion l, to which is fastened the hand-crank L.

The annular wheel K turns on the round bolt i, which is fastened to the upright A by the nut n.

Upon the outer end of the bolt or shaft i is secured an arm, p, extending at right angles to the bolt i, and in the direction of the teeth of the annular wheel K.

To the end of the arm p is pivoted the pinion l, to which is secured, eccentrically, the hand-crank L, by operating which the machine is set in motion.

M designates the descending frame, by means of which the saw is guided down through the log. It consists of a horizontal shelf, grooved crosswise, for the passage to and fro of the sliding bar H.

The ends of this shelf are dovetailed into upright cheeks h h, grooved perpendicularly, on the outside, to fit the guide-posts a a, on which they slide.

Lengthwise, along the middle of the upper surface of the shelf M, is secured the rib f, fastened also at each end by being let into the cheeks h h.

Into this rib, at each end, are fastened the screws or ring-bolts e e, to which is attached a bail m, linked above, at its central point, to the end of the ring-

In order to form a fulcrum for this lever, a support, R, is fastened to the centre of the girder E.

S designates a spring-catch, fastened to the centre of the girder E, in such a position, that when the end of the lever F is brought down, thereby raising the saw to its highest elevation, it will catch and hold the lever-end, thus holding up the saw until it is brought over the log to be sawn.

The operation of this machine is as follows:

The saw being raised by the lever F, this machine is brought alongside the log or tree which is to be sawn, in such a manner that the saw will extend over it. The spring S is now drawn back, releasing the lever F, and allowing the guide-shelf M to descend until the saw rests on the top of the log. The crank L is now turned by hand, rotating the pinion l, which in turn causes the annular wheel K to revolve, by engaging with its outer circle of teeth. The inner circle of the teeth of the wheel K, at the same time engaging with the pinion u, causes it to revolve, thereby turning the crank-shaft s', which, through the right-angled lever V, and pitmen r and z, gives the saw G the necessary motion, the sliding bar H keeping the saw always horizontal.

In the use of this machine, there is no necessity of raising the log on skids. It can be sawn as it lies on the ground, and the saw will pass entirely through the log, square down to the ground.

The pitman z is adjustable on the perpendicular arm of the right-angled lever V, so that this arm may be made longer or shorter, thus regulating the amount of power communicated to the saw, and the length of its stroke.

What we claim as our invention, and desire to secure by Letters Patent, is—

1. In combination with the pendent guide M, sliding bar H, and pitman z, the adjustable right-angled lever V, constructed and arranged to operate as specified.

2. The arrangement, herein shown, of the double-rim annular wheel K, pinions l and u, crank-shaft s', and crank L, for operating a cross-cut saw, as specified.

3. The sawing-machine, herein described, having the pinions l and u gearing with the double-rim annular wheel K, crank-shaft s', pitman r, right-angled lever V, adjustable pitman z, sliding bar H, and pendent sliding guide M, with lifting-lever F, and spring-catch S, all constructed and arranged to operate a cross-cut saw, as specified.

In testimony that we claim the above, we have hereunto subscribed our names, in the presence of two witnesses.

E. R. HALL.
WM. H. TOWN.
